UNITED STATES PATENT OFFICE.

JOHN ASTROM, OF FORT WAYNE, INDIANA, ASSIGNOR TO FORT WAYNE ENGINEERING
AND MANUFACTURING COMPANY, OF FORT WAYNE, INDIANA.

DEEP-WELL-PUMP HEAD.

1,241,604.

Specification of Letters Patent.

Patented Oct. 2, 1917.

Application filed March 12, 1917. Serial No. 154,147.

To all whom it may concern:

Be it known that I, JOHN ASTROM, a citizen of the United States, and resident of Fort Wayne, in the county of Allen and State of Indiana, have invented certain new and useful Improvements in Deep-Well-Pump Heads; and I do hereby declare that the following is a full, clear, and exact description thereof.

10 The present invention relates to new and useful improvements in head structures for pumps, and more particularly for deep well pumps, wherein a relatively great vertical strain is procured, with very little lateral strain.

A distinguishing feature of pump heads of the type heretofore provided is the provision of a relatively heavy frame work having portions machined to form the bearings 20 of the head and to form a vertical guide for the cross head of the pump rod. Inasmuch as it is necessary in structures of this nature to provide only for a working strain in the general direction of movement of the pump 25 rod, or corresponding member, it is primarily the object of the invention to provide a structure which will efficiently meet this strain and which comprises an exceedingly simple and light structure by the elimination of superfluous parts not particularly acting to meet said strain.

More specifically, it is an object to provide an arrangement including upstanding columns which form the body of the head 35 frame and which serve as guides for the pump rod cross head, and as securing means for the pulley shaft of the head, whereby the pinion of the pulley shaft which engages the gear wheel of the crank shaft may be 40 at all times held in proper mesh therewith.

With the above and other objects and advantages in view, the invention resides more particularly in the novel combination, formation and arrangement of parts herein- 45 after described and pointed out in the appended claims.

In the drawings:

Figure 1 is a side elevational view of a deep well pump head constructed in accordance with the present invention, portions thereof being broken away to more clearly disclose the structure.

Fig. 2 is an edge elevational view of the pump head.

55 Fig. 3 is a transverse sectional view

through the head on the line 3—3 of Fig. 1, showing more particularly the securing means for the fly wheel shaft.

Fig. 4 is a transverse sectional view on the line 4—4 of Fig. 1 showing the pump 60 rod cross head.

Referring now more particularly to the accompanying drawings, 5 designates a cast metal bed plate in one end of which are provided a pair of bored sockets 6 into which 65 are pressed the lower ends of a pair of up-standing tubular columns 7, the upper ends of these columns extending into the lower socketed ends of bearing blocks 8, and the socket portions of said blocks being prefer- 70 ably split and provided with outstanding ears 9, through which are passed clamping bolts 10 whereby the bearing blocks are rigidly yet detachably secured to the columns. Transversely journaled in these bearing blocks are the end portions of a crank 75 shaft 11, one end of which extends past its adjacent bearing and carries a gear wheel 12 and journaled on the crank portion of the crank shaft 11 is a pitman 13 which is 80 provided with a bearing head 14 at its lower end receiving a pin 15 carried by the pump rod cross head.

This cross head comprises a pair of sleeves 85 16 slidably mounted on the columns and connected by a web portion 17. The sleeves and web portion are provided with a single horizontal bore 18 for the insertion of the pin 15, the bearing head 14 of the pitman engaging in a socket formed in the web portion 17. Connected with the cross head, as by threadedly engaging its upper end in the web portion 17 thereof is a pump rod 19. It is noted that the principal stresses of 90 operation in this structure originate from the opposite forces at the cross head and the bearings of the crank shaft, and these stresses are met directly by the columns 7, which also serve as the guides for the cross head sleeves.

To support a shaft 20 carrying a pinion 21 for meshing engagement with the gear wheel 12 of the crank shaft, a pair of split sleeves 22, including outstanding ears 23 and clamping bolts 24 passed therethrough, are 105 clamped on the columns between the bearing blocks 8 and the cross head and these sleeves carry laterally projected bearing arms 25 in which the shaft 20 is mounted. These arms project a sufficient distance to 110

provide clearance for the lateral movement of the pitman 13. By this arrangement, it is noted that the columns in addition to their functions heretofore stated also serve to support the pinion shaft, and more particularly in a manner whereby its pinion 21 may be accurately adjusted for mesh with the gear wheel 12. The shaft 20 may be driven by any desired means, in the present instance 10 a belt wheel 26 being provided thereon.

While I have described my invention in connection with a deep well pump structure for which it is particularly adapted, it is obvious that the invention may find use in 15 other fields wherein an oscillatory movement is procured by the use of a crank and pinion, and wherein the strain of operation would be mainly longitudinal of the direction of oscillatory movement.

20 What is claimed is:

1. A structure of the class described comprising a pair of parallel members, a crank shaft journally carried by adjacent ends of said members, a cross head slidably mounted on said members and a pitman connecting the cross head and crank shaft.

2. A structure of the class described comprising a pair of parallel members, a crank shaft journally carried by adjacent ends of 30 said members, a cross head slidably mounted on said members, a pitman connecting the cross head and crank shaft, a gear on the crank shaft, a second shaft journally supported by said members and a gear on 35 said second shaft meshing with the first named gear.

3. A structure of the class described and comprising a pair of parallel members, a transversely disposed crank shaft carried by 40 adjacent ends of said members, a cross head including sleeves slidably mounted on said members and a connecting web portion and a pitman connected with the crank shaft and cross head.

45 4. A structure of the class described comprising a pair of parallel members, a crank

shaft journally carried at adjacent ends of said members, a cross head including sleeves slidably mounted on the members and a connecting web portion provided with a socket, 50 one sleeve and said web being provided with a transverse bore intersecting the socket, a pin disposed in said bore and a pitman connected with the crank shaft and mounted on said pin. 55

5. A structure of the class described comprising a pair of parallel members, a transversely disposed crank shaft journally carried by adjacent ends of said members, a cross head slidably carried by said members, a pitman connecting the crank shaft and cross head, sleeves adjustably clamped on said members between the cross head and crank shaft, bearing arms projecting from said sleeves, a second shaft journalled in said 60 arms and intermeshing gears on said second shaft and the crank shaft.

6. A deep well pump head comprising a base portion, a pair of columns upstanding from said base portion, a crank shaft transversely journally carried by the upper ends 70 of the columns, a cross head slidably carried by the columns and a pitman connecting the crank shaft and cross head.

7. A deep well pump head comprising a 75 base portion, a pair of columns upstanding from said base portion, a crank shaft transversely journally carried by the upper ends of the columns, a cross head slidably carried by the columns, a pitman connecting the crank shaft and cross head, a drive shaft adjustably carried by the columns and intermeshing gears on the drive shaft and crank shaft. 80

In testimony that I claim the foregoing I 85 have hereunto set my hand at Fort Wayne, in the county of Allen and State of Indiana, in the presence of two witnesses.

JOHN ASTROM.
